UNITED STATES PATENT OFFICE.

SHAVERKSHA D. MASTER, OF BOMBAY, INDIA.

ROTARY ENGINE.

1,385,880.

Specification of Letters Patent. Patented July 26, 1921.

Application filed July 11, 1919, Serial No. 310,037. Renewed December 27, 1920. Serial No. 433,427.

To all whom it may concern:

Be it known that I, SHAVERKSHA DORABJI MASTER, a subject of the King of England, residing at Bombay, India, have invented new and useful Improvements in Rotary Engines, of which the following is a specification.

The general object of my present invention is the provision of a simple rotary engine that is reliable, in operation, is possessed of high capacity, and is susceptible of being controlled by one having little experience in steam engineering.

While designed more particularly to be actuated by steam, it is not to be understood that my invention is restricted to a steam engine, inasmuch as certain parts of my improvement may be embraced to advantage in compressed air and internal combustion engines.

With the foregoing in mind, the invention in all of its details will be fully understood from the following description and claims, when the same are read in connection with the drawings, accompanying and forming part of this specification, in which:

Figure 1 is a longitudinal vertical section of a rotary engine constructed in accordance with my invention.

Fig. 2 is an enlarged detail section illustrative of the lubricating and oscillatory abutment.

Fig. 3 is a detail view illustrative of the application of a spring to the said abutment.

Fig. 4 is an enlarged detail section showing the several members of the piston comprised in my novel engine.

Fig. 5 is a diagrammatic view hereinafter specifically referred to.

Fig. 6 is a detail section showing the manner in which the blades of the piston are connected with the shaft of the engine.

Fig. 7 is an enlarged detail section illustrative of one of the oscillatory members carried by the piston body and receiving one of the piston blades.

Fig. 8 is a detail, enlarged section showing the packed shoe on one piston blade.

Fig. 9 is a section taken at right angles to Fig. 8 and showing a different type of spring.

Fig. 10 is an enlarged detail section illustrating a form of packing for the side edges of the piston body.

Figs. 11, 12, 13 and 14, are detail views

of modifications hereinafter specifically referred to.

Similar numerals designate corresponding parts in Figs. 1 to 10, to which reference will first be had.

Upon a bed 1 I fix a circular casing 2, and at its top I provide the said circular casing with a housing 3 in which is a filling aperture 4 for lubricant. The interior of the housing 3 is in communication with the interior of the casing 2, and in the said housing is arranged a hollow oscillatory abutment 5. The said abutment 5 is provided with an aperture 6 in its top larger than the aperture 4, in about the proportion illustrated, and adapted to enable oil fed through the aperture 4 to enter the interior of the abutment. The inner face of the abutment 5 is slightly concave in the direction of its width, as indicated by 7, and leading from the interior of the abutment 5 to the said face 7 are minute ducts 8 for the feed of oil to the perimeter of the rotary piston body 9, hereinafter described. One of the trunnions of the abutment 5 is provided with a crank 10, Fig. 3, and coöoperating with the said crank 10 is a spring 11 that coöperates with the crank 10 in yieldingly holding the abutment against the perimeter of the piston body 9 at one side of the abutment. In this manner a permanent joint is effected between the piston body 9 and the abutment 5.

It will be manifest from the foregoing that the abutment 5 serves a two-fold function, and in that way contributes to the simplicity and efficiency of the engine.

The circular piston body 9 is arranged eccentrically to the engine shaft 12 which is journaled in the side walls or heads of the casing 2 and may be provided with a flywheel and with a band pulley or other driving medium, though I have not deemed it necessary to illustrate these last named elements. Within the casing 2 the shaft 12 is provided with sockets 13 each of which describes more than half of a circle, and in the said sockets 13 are disposed circular journals 14 at the inner ends of piston blades 15, whereby as will be readily understood the piston blades are fixedly and strongly connected of themselves to the shaft 12 without the assistance of extraneous means.

Journaled in the circular wall of the piston body 9 so as to oscillate about their axes

therein, are rocking members 16 which in addition to their oscillatory capacity are adapted to slide upon the piston blades 15 with a view to carrying the piston blades 5 around with the body 9 without interfering with the rotation of the body 9 or the sliding of the members 16 on the blades 15, and without permitting the passage of steam or other fluid under pressure from the space 17 10 between the circular body 9 and the circular wall of the casing 2.

At opposite sides of the housing 3 are ports 18 and 19 for the admission and exhaust of fluid under pressure.

15 The side edges of the piston body 9 are packed after the manner clearly illustrated in Fig. 10. By reference to Fig. 10 it will be observed that each edge of the piston body 9 is provided with a circular groove 20 in opposition to one side wall or head 21 of the casing 2, and in the said groove 20 is arranged a hollow body 22, preferably of sheet steel and with its edges 23 separated. The said hollow body 22 is connected by 25 screws 24 with the piston body, and in the same is packed a mass of asbestos 25, which by reason of its resiliency or elasticity is designed to press the free portions of the hollow body 22 against the head 21, and thereby adequately pack the piston body without the creation of undue friction. When both edges of the circular piston body 30 9 are packed in the manner described, it will be manifest that the escape of steam or other fluid under pressure from the space 17 to the space within the circular body 9 will be rendered practically *nil*.

At this point I would have it understood that the peculiar and advantageous packing means shown in Fig. 10 may, when deemed expedient, be used between the side edges of the piston blades 15 and the heads or sides 17 of the casing 2.

At their outer ends the piston blades 15 45 are provided with shoes 30 that extend in the direction of rotation and are exteriorly curved in conformity to the circular wall of the casing 2. In the said shoes 30 are pockets 31, and movable in the said pockets and 50 opposed to the circular wall of the casing 2 are packing members 32, each of which is backed by one or more springs 33 in order to yieldingly press the said members 32 outwardly and thereby prevent the escape of 55 steam or other fluid under pressure past the packed piston blade. The springs may be of coil type as shown in Fig. 8, or of the form shown in Fig. 9, as desired.

In the practical use of my novel engine it 60 will be observed that either of the apertures 18 or 19 may be employed as the induction port and the other aperture as an eduction port, and from this it follows that the engine is susceptible of being readily reversed. It 65 will also be understood in this connection

that the oscillatory abutment 5 is adapted to accommodate itself to the direction of rotation of the piston and serve adequately as a cut-off or separating means between the ports 18 and 19 irrespective of which port 70 is employed as the induction port.

In Fig. 11 I show a modified means for packing the shoes of the piston blades. By reference to Fig. 11 it will be readily understood that the shoe 30^a is provided with 75 packing members 32^a and 23^a, while between the said members 23^a and 32^a is interposed a rocking-packing member 40 between a shoulder of which and the recess wall in the shoe is interposed a spring 41. The packing 80 member 40 is adapted to oscillate with a view to serving efficiently irrespective of the direction in which the shoe is moved. The packing member 32^a is backed by a spring 42, and the packing member 22^a is of the 85 general type of the packing member 22 shown in Fig. 10; the said member 22^a being designed to be filled with compressed asbestos as shown and to be yieldingly pressed by the resiliency of the said asbestos 90 against the opposed circular wall of the casing.

In Fig. 12 I show a modified packing for the side edges of the piston blades. In the construction of said figure, the blade 9^a is 95 provided in its edge with a recess 50 in which is disposed an oscillatory and shoudered packing member 51, between the shouder 52 of which and the piston blade is located a spring 53 designed to yieldingly 100 press one portion of the members 51 against the casing head, and thereby improve the packing quality of the member 51.

In Fig. 13 the piston blade 9^b is recessed at 60 and is designed to carry a packing member or strip 61, backed by asbestos 62 or other resilient material under tension.

As shown in Fig. 1, a plurality of regulating cocks 70 are carried on the circular wall of the casing 2 and are connected with the interior of the said casing. These cocks are stationary and one or the other is used according to the cut-off desired, the cut-off being indicated by A, C, A', A², B, B' and B² in Fig. 5.

In Fig. 14 I show a modified packing which may be employed to advantage in the piston blade shoes or in the side edges of the piston body in the discretion of the manufacturer of the engine. The said packing 120 comprises two members 80 arranged side by side in interlocked relation and disposed in recess 81, interposed spring means 82 calculated to yieldingly crowd the members 80 against the wall of the recess, and spring 125 means 83 arranged to yieldingly press the members 80 outwardly as a unit.

It will be apparent from the foregoing that I have provided a simple and inexpensive construction of rotary engine in which 130

engine friction is averted without seriously impairing the efficiency of the engine.

Having described my invention, what I claim and desire to secure by Letters-Patent, is:

1. In a rotary engine, the combination of a circular casing, a circular piston body disposed eccentrically in the casing, a housing in communication with the casing in close proximity to the perimeter of the piston body and having a filling aperture for lubricant, and an oscillatory hollow abutment opposed to the perimeter of the piston body and adapted to lubricate the same and having an aperture in registration with the first-named aperture.
2. In a rotary engine, the combination of a circular casing, a circular piston body disposed eccentrically in the casing, a housing in communication with the casing in close proximity to the perimeter of the piston body and having a filling aperture for lubricant, an oscillatory abutment opposed to the perimeter of the piston body and adapted to lubricate the same and having an aperture in registration with the first-named aperture, a crank fixed with respect to said abutment, and a spring coöperating with said crank for yieldingly pressing a portion of the abutment against the perimeter of the piston body.
3. In a rotary engine, the combination of a casing, a rotary hollow piston body located eccentrically in the casing, a shaft arranged centrally of the casing and off the center of the piston body, oscillatory members mounted in the wall of the piston body, and piston blades connected with the shaft and slidably arranged in the oscillatory members and having outer portions opposed to the inner side of the casing; the said shaft having circular sockets, and the piston blades being journaled with their inner ends disposed in said sockets and retained by the socket walls describing more than halves of circles.
4. The combination in a rotary engine, of a shaft having longitudinal sockets of circular form that extend in the direction of its length, describe more than half of a circle, and are open at the perimeter of the shaft, and piston blades having journal portions of circular form in cross-section disposed in said sockets.
5. In a rotary engine, the combination of a casing circular in form, a piston in the casing and having blades with shoes opposed to the circular wall of the casing, auxiliary spring-pressed packing members carried in the shoes, and oscillatory yieldingly-pressed packing members carried in the shoes and opposed to the circular wall of the casing and spaced from the said auxiliary, spring-pressed packing members and opposed to the circular wall of the casing.

In testimony whereof I affix my signature.

SHAVERKSHA D. MASTER.
